Attorney

UNITED STATES PATENT OFFICE.

GEORGE W. DOWTHARD, OF LUMBERPORT, WEST VIRGINIA.

ARMOR FOR SHIPS.

1,264,380.

Specification of Letters Patent. Patented Apr. 30, 1918.

Application filed February 9, 1918. Serial No. 216,299.

To all whom it may concern:

Be it known that I, GEORGE W. DOWTHARD, a citizen of the United States, residing at Lumberport, in the county of Harrison and

5 State of West Virginia, have invented certain new and useful Improvements in Armor for Ships, of which the following is a specification, reference being had to the accompanying drawings.

10 This invention relates to certain improvements in armor for ships and has relation more particularly to an armor especially designed and adapted for use in connection with battle ships and it is an object of the 15 invention to provide a novel and improved armor whereby the hull of a ship is effectively protected against injury incident to the force of a projectile.

It is also an object of the invention to 20 provide a novel and improved armor which includes a plurality of shanks extending outwardly from the hull of a ship with the outer ends thereof provided with heads, said shanks being of varying lengths and 25 the heads of such diameter as to prevent a projectile from striking the hull proper of a ship.

The invention consists in the details of 30 construction and in the combination and arrangement of the several parts of my improved armor for ships whereby certain important advantages are attained and the device rendered simpler, less expensive and otherwise more convenient and advantageous 35 for use, as will be hereinafter more fully set forth.

The novel features of my invention will 40 hereinafter be definitely claimed.

In order that my invention may be the better understood, I will now proceed to describe the same with reference to the accompanying drawings, wherein:

Figure 1 is a diagrammatic view in top plan illustrating an embodiment of my invention; and

Fig. 2 is a fragmentary view in side elevation illustrating the relative positions of the shanks as herein employed.

As disclosed in the accompanying drawings 50 H denotes the outline of a hull of a ship and extending outwardly therefrom are the shanks 1 and 2 of predetermined length and preferably formed of hard steel. The shanks 1 are of a length greater than the 55 shanks 2. The outer ends of the shanks 2 are provided with the heads 3 formed of

hardened steel and preferably conical in form with the apices thereof outwardly directed. The heads 3 are also of such major diameters as to have the heads 3 of the 60 shanks 1 partially overlying the heads 3 carried by the shanks 2. Also extending outwardly from the hull H are the tapered shanks 4. The shanks 4 have their outer extremities terminating inwardly of the 65 heads 3 carried by the shorter shanks 2 and are suitably positioned between the shanks 1 and 2. By this arrangement it will be perceived that it is substantially impossible for a projectile in its direct line of travel 70 to come into contact with the hull H. The projectile will strike the heads 3 of the shanks 1 and 2 and if not thrown by said heads away from the hull H the projectile will come into contact with the shanks 4. 75 By this means it will be at once self-evident that the hull H of the ship is effectively protected against injury from projectiles.

It is also desired that a shield S be suitably supported by the hull H and disposed 80 entirely around the ship at a predetermined point in advance of the shanks 1 and said shield preferably extends below the water line. By this arrangement it will be at once self-evident that the shanks 1, 2 and 85 4 are effectively concealed from the enemy so it will be impossible for the enemy to determine what means are employed to protect the vessel against injury from the projectiles thrown thereagainst. The shield S 90 may be provided with suitable openings to permit the discharge of any of the guns carried by the ship and to which the shield would otherwise offer obstructions. It is also to be noted that the shield S is to be 95 provided with suitable openings to permit desired observations.

From the foregoing description, it is thought to be obvious that an armor for ships constructed in accordance with my invention is particularly well adapted for use by reason of the convenience and facility with which it may be assembled and operated and it will also be obvious that my invention is susceptible of some change and 100 modification without departing from the principles and spirit thereof and for this reason I do not wish to be understood as limiting myself to the precise arrangement and formation of the several parts herein 110 shown in carrying out my invention in practice except as hereinafter claimed.

I claim:

In combination with a hull of a ship, a plurality of shanks extending outwardly therefrom, heads carried by the outer extremities of the shanks, said heads being substantially conical in form with their apices outwardly directed, said shanks being of different lengths, the heads of the longer shanks partially overlying the heads of the shorter shanks, and tapered shanks

extending outwardly from the hull and terminating inwardly of the heads of the shorter of the first named shanks.

In testimony whereof I hereunto affix my signature in the presence of two witnesses. 15

GEORGE W. DOWTHARD.

Witnesses:

JAMES MCCOLLUM,
PHIL HICKS.
